UNITED STATES PATENT OFFICE.

JOHN BENJAMIN FLOWERS, OF ALBANY, NEW YORK.

PROPELLER.

1,405,910.

Specification of Letters Patent.

Patented Feb. 7, 1922.

Application filed September 22, 1920. Serial No. 411,979.

To all whom it may concern:

Be it known that I, JOHN BENJAMIN FLOWERS, a citizen of the United States, residing at 339 Hamilton St., Albany, in the 5 county of Albany and State of New York, have invented certain new and useful Improvements in Propellers, of which the following is a specification.

This invention relates to propellers generally and more particularly to a propeller which will provide a uniform thrust and which will operate with comparatively little noise. A study of the cause of propeller noise shows that at least one half thereof is 10 due to the pulse of air caused by each propeller blade of the propellers of the present type during each revolution when turning under power. The air in front of the blade in its rotation, is highly compressed, is forced 15 past the propeller, and rushes into the low pressure area created directly behind the blade as it progresses with its rotation. While the air is still in violent disturbance 20 behind the blade it is struck by the second blade in its rotation. This rush of air to the low pressure area together with the impact of the following blade upon the disturbed air there creates a very violent disturbance or pulsation, with the noise incident thereto, and the propeller itself is also 25 thrown into a violent vibration.

Obviously, with the propellers of the types at present used, that is of a discontinuous spiral, as the two, three, and four blade of 30 propellers now in use, it would be impossible to do away with this propeller noise. It is the purpose of this invention to provide a propeller with a comparatively uninterrupted and uniform thrust from front to rear, which will operate with but little vibration and noise.

Most of the noise of the propeller operation being due to the pulse of air caused by each blade, it is proposed to obviate the same 45 by re-designing the propeller to give a constant thrust over the entire area covered by the propeller during one revolution. This propeller blade should have a diameter equal to the diameter of a circle described by the 50 tip of the usual propeller blade.

It is proposed that the propeller have the shape of a double threaded screw and the blade will be in the form of a thin sheet of corrugated steel of extremely high tensile 55 strength in order to stand the great centrifugal force.

Since a large part of the noise of the propeller operation is due to the vibrations of the blade itself it is believed that that also could be eliminated by this construction, for 60 as the thin steel blade over the entire revolution of the propeller will ride on a cushion of air, the vibrations will be critically damped during the entire revolution.

A noiseless propeller is highly desirable 65 for commercial planes for it has been found that the noise of the present type of propeller is very objectionable to passengers. For military use it is necessary to do away with this propeller noise or the enemy will 70 be fore-warned of the approach of the airplane. The use of noiseless propellers will, therefore, vastly increase the use of airplanes for reconnaissance.

This invention is primarily intended as 75 an improvement for propellers for use in aircraft but the inventor does not limit himself thereto.

In the accompanying drawings: Fig. 1 is a top view in perspective with 80 portion broken away to show spoke arrangement;

Fig. 2 is a front elevation of the propeller and shaft;

Fig. 3 is a side elevation of a portion of 85 the propeller to show the detail of attachment of the spokes and blade to the shaft.

Referring to the figures in detail the propeller consists of two driving portions, spiral in shape and of substantially 360° 90 each in extent and attached by means of spokes to the shaft. 1 is a propeller shaft which is attached to the outer driving portion 3 of the propeller by spokes 2. The driving portions 3 are each built of corrugated sheet metal of high tensile strength and are crimped with a T-shaped upset at the inner edge as 4 to provide means for fastening to the spokes and at the outer edge as at 5 in a manner to provide rigidity to 100 the structure of the blade. The end of the spokes 2 are externally screw threaded and adapted for the reception of fastening nuts 6 and keys 8 for securing a driving portion 3 to a shaft 1. The driving portion 3 has a 105 cut-away portion 7 to provide space for the installation and adjustment of nuts 6. Spokes 2 are fastened in any desired manner to the propeller shaft and are, in the illustrated embodiment, inset and brazed to the 110 shaft.

The driving portion is of such structure

as to extend from the outer periphery of the propeller inwardly to a point substantially one-half the way to the shaft. It has been found that the only useful thrust is performed by such a portion of a propeller for at any point inward thereof the speed of rotation is so small as to prevent the production of any great thrust at such a point.

It is proposed to cover the spokes of the 10 inner driving portion, as shown at 9 and 10, with a material of somewhat lighter structure than the outer driving portion. It is necessary that the outer portion be of high tensile strength on account of the great centrifugal force and thrust to which it is subjected. The outer driving portions are in the shape of a helix of substantially 360° and are balanced as nearly as possible by means of nuts 6 and washers 11, which may be supplied as shown.

My device operates as follows: By reason of the fact that the driving portions of my propeller extend throughout the whole cycle of 360° a thrust of uniform force will be produced throughout the whole thereof. This will provide for a continuous air stream which will be free from the pulses caused by the beating of the blades of the present type of propellers and will do away with the vibration of the propeller that would be incident to such pulses. It will be seen, then, that the noise of propeller operation will thus be greatly diminished and a uniform thrust with its consequent benefits obtained.

35 I claim:

1. In a propeller, a shaft, a driving portion of material of low relative thickness formed in two spiral blades of approximately 360° extension each, means connecting said

driving portion to said shaft, and adjustable means for balancing the same.

2. In a propeller, a shaft, an outer driving portion in the form of a spiral blade approximately 360° in extent, a plurality of spokes projecting from the shaft toward the 45 blade and having adjustable connection with the latter, and balancing nuts threaded on the spokes for engagement with the blade.

3. In a propeller, a shaft, driving portions of material of low relative thickness and of high tensile strength formed in two spiral blades of approximately 360° extension each, spokes for connecting said blades to the shaft, and means for stream-lining such spokes in a line of the spiral of the outer driving portion.

4. In a propeller, a shaft, driving portions of material of low relative thickness and of high tensile strength formed in two spiral blades of approximately 360° extension each, 60 spokes for connecting said blades to the shaft, and means for stream-lining such spokes in the line of the spiral of the outer driving portion, said means being comprised of a lighter material than that used in the 65 outer driving portion.

5. In a propeller, a shaft and an outer driving portion of material of high tensile strength, means connecting the same, and an inner driving portion of lighter material.

6. In a propeller, a shaft, an equal driving portion of material of high tensile strength, crimped to provide additional strength and an inner driving portion of lighter material.

In testimony whereof I have affixed my 75 signature.

JOHN BENJAMIN FLOWERS.
